UNITED STATES PATENT OFFICE.

WINFIELD S. REEVE, OF RICEVILLE, IOWA.

BLACKSMITHS' SHEARS.

SPECIFICATION forming part of Letters Patent No. 226,105, dated March 30, 1880.

Application filed July 9, 1879.

To all whom it may concern:

Be it known that I, WINFIELD S. REEVE, of Riceville, in the county of Mitchell and State of Iowa, have invented a new and Improved Blacksmiths' Shears, of which the following is a specification.

The object of my invention is to provide an improvement in trimming-shears for blacksmiths' use.

10 The invention consists in connecting the cam-lever with the movable jaw by a slotted plate, so that the operator may stand behind and over his work, thus being enabled to cut to a line.

15 In the accompanying drawings, Figure 1 is a side elevation of my improvement, and Fig. 2 is a top plan or view of the same.

Similar letters of reference indicate corresponding parts.

20 Referring to the drawings, A is the stationary jaw of the shears, having a cutting-edge, a, and on its upper side, parallel thereto, a guard, b, through or under which the metal is thrust and by which it is held, so as to be 25 acted on by the shears.

B is the upper or movable jaw, pivoted at one end to the side of A, and at the opposite end held between upright guides C C. In the guides, above the jaw, is fulcrumed a lever, 30 D, having on its under side, at the fulcrum, an eccentric face or cam, D', in one side whereof is a semicircular groove, e, parallel to the face of the cam.

E is a link having two parallel sides. In 35 one upper angle is a pin or stud, d, which projects into the groove e. In the center is a diagonal slot, e, through which a headed stud is passed and entered into the movable jaw.

A guard, F, fixed to the side of the inside 40 guide, extends over the link E and in line with its outside edge. This furnishes a guard to keep the link in connection with the cam, and

at the same time a guide for leading it up and down.

On the side of the movable jaw next to the 45 fixed one is a blade or cutting-edge, a', which moves with a shear cut against the edge of a as the jaw is moved down.

By operating the lever on its fulcrum it draws the link up, and this, in turn, elevates the jaw 50 B; but when the lever is turned down the cam-face D', operating on the end of the jaw, forces it down with great power, causing the blade a' to move across a with a shear cut, so as to sever or trim any object placed between the 55 jaws. The movement thus obtained for the shears is a powerful one, and the operator can stand close up to his work when using the shears.

I am aware that it is not broadly new to 60 connect a cam-lever by an intermediate connection with the movable jaw of a shear or punch; but my device is believed to have practical advantages. When the jaw and lever are connected by my diagonally-slotted plate the 65 plate is caused to move the length of the diagonal of a parallelogram while the jaw moves only the length of one side, thus gaining power at the expense of velocity. Also, the lever being thrown directly over the movable jaw B, 70 one workman only is required where two were heretofore necessary, the same man being able to feed and operate mine at the same time.

What I claim as new and of my invention is—

75 In combination with the cam-slotted lever D and the movable jaw B, the diagonally-slotted plate E, connected with lever and jaw by pins, as shown and described.

WINFIELD SCOTT REEVE.
